UNITED STATES PATENT OFFICE

FREDERICK D. HANSEN AND HERBERT W. TINKER, OF MILWAUKEE, WISCONSIN, AS-SIGNORS, BY MESNE ASSIGNMENTS, TO FEDERAL PRESSED STEEL CORPORATION, OF MILWAUKEE, WISCONSIN, A CORPORATION OF DELAWARE

DESIGN FOR A TIRE COVER

Application filed July 20, 1929. Serial No. 32,146. Term of patent 14 years.

To all whom it may concern:

Be it known, that we, FREDERICK D. HANSEN and HERBERT W. TINKER, citizens of the United States, residing at Milwaukee, county of Milwaukee, State of Wisconsin, have invented a new, original, and ornamental Design for Tire Cover, of which the following is a specification, reference being had to the accompanying drawings, forming a part hereof.

Figure 1 is a front elevation of the tire cover showing our new design;

Fig. 2 is an end view of the cover, looking in the direction of the arrow 2 in Fig. 1; and Fig. 3 is a section along the line 3—3 in Fig. 1, looking in the direction of the arrows.

We claim:

The ornamental design for a tire cover as shown.

FREDERICK D. HANSEN.
HERBERT W. TINKER.
